CLAIM

The ornamental design for an analysis device, as shown and described.

DESCRIPTION

FIG. 1 is a top perspective view of an analysis device; FIG. 2 is a bottom elevation view thereof;

FIG. 3 is a top elevation view thereof;

FIG. 4 is a right side elevation view thereof;

FIG. 5 is a left side elevation view thereof;

FIG. 6 is a front view thereof; and,

FIG. 7 is a rear view thereof.

The broken lines illustrate portions of the analysis device that form no part of the claimed design.
